UNITED STATES PATENT OFFICE.

FRANK D. LEWIS, OF DENVER, COLORADO.

CENTRIFUGAL AMALGAMATOR AND CONCENTRATOR.

Application filed March 6, 1925. Serial No. 13,482.

My invention relates to an improved apparatus for the amalgamation of gold, and the concentration of other minerals.

The objects of my invention are:

5 First: To provide a practical and economical centrifugal amalgamator and concentrator for the recovery by amalgamation, employing mercury, gold in all its forms subject to amalgamation, such as nuggets, 10 shot gold, flour gold, and microscopic gold, from any and all gold bearing materials, such as free gold ore pulp, roasted ore pulp, and placer sands or gravel.

Second: To provide a practical and economical centrifugal amalgamator and concentrator for the recovery by concentration, platinum, rusty gold not subject to amalgamation, gold coated with other minerals not subject to amalgamation, gold coated with 20 oil or any other substance which may interfere with its affinity for mercury, iron, and all other minerals subject to concentration.

Third: To provide a centrifugal amalgamator and concentrator that will accomplish 25 both amalgamation and concentration efficiently at the same time or at one operation, employing the same power, water and labor.

Fourth: To provide a centrifugal amalgamator and concentrator in which centrifugal force is the basis of separation and the 30 medium of separation for both the amalgamation and the concentration, the metallic elements contained in the products under 35 treatment being stratified according to their respective specific gravities at or adjoining the inner surfaces of the concentrating and amalgamating elements, where they are under the greatest pressure, the momentum 40 herein employed increasing the differential of the various metallic elements many times as compared with their differential when not under pressure, thus a very high degree 45 of extraction is attained in the form of forced amalgamation and forced concentration, and the concentration may be selective if so desired.

Fifth: To provide a centrifugal amalgamator and concentrator so constructed as 50 to minimize the loss of mercury in the form of floured mercury or otherwise.

Sixth: To provide a centrifugal amalgamator and concentrator so constructed as to 55 have an unlimited number of adjustments at all points of congestion, thus controlling the time element of the product under treat-

ment, also controlling the flow of concentrates.

I attain these objects by the mechanism illustrated in the accompanying drawings 60 in which:

Figure 1 is a sectional elevation of a centrifugal amalgamator and concentrator embodying my invention.

Figure 2 is a plan view of the same. 65

Figure 3 is a horizontal section through the machine on line 3—3 of Figure 1 looking down into the machine from its top.

Figure 4 is a horizontal sectional view 70 on the line 4—4 of Figure 1.

Figure 5 is a top plan view of the bottom plate of the rotatable gold saving member of the machine.

Figure 6 is a vertical sectional view of the same on the line 6—6 of Figure 5. 75

Figure 7 is a vertical sectional view of the outside member of a two-part rotatable gold saving member.

Figure 8 is a vertical sectional view of the other or inside member which is removably connected to the member shown in 80 Figure 7.

Figure 9 is a vertical sectional view of the adjustable ring-like member which controls the discharge of the concentrates from 85 the upper end of the outside member of the rotatable element.

Figure 10 is a bottom plan view of Figure 9. 90

Figure 11 is an elevation partly in section of one of the hollow bolts, through which mercury is introduced to the uppermost mercury-receiving pocket.

Figure 12 is a vertical sectional view—enlarged—through a portion of the upper 95 end of the rotatable element of the machine showing more clearly the manner of controlling the discharge of the concentrates from the cylinder.

Figure 13 is a sectional view of a portion 100 of the bottom plate of the cylinder 3, taken on the line 13—13 of Figure 5, and

Figure 14 is a sectional view of a portion of the upper end of the machine, taken on the line 14—14 of Figure 2 and showing the 105 manner of adjusting the ring-like water box in the upper end of the machine.

Figure 15 is a detail sectional view showing the manner of feeding ore and water to the inlet pipe at the upper end of the machine, and 110

Fig. 16 is a sectional view of a portion

of the upper end of the machine, showing a modification in the outermost concentrating and amalgamating cylinder.

Similar letters of reference refer to similar views through the several views.

The apparatus can be made in different sizes to treat from about one hundred to a thousand or more cubic yards of placer dirt each working day.

10 I preferably illustrate, however, a machine that is about four feet in height by about two feet in diameter which will treat about one hundred cubic yards of placer dirt per day.

15 The apparatus consists of a stationary base plate or foundation member 1, and a stationary body member 2, which rests on the base plate 1, and extends upward from it about one-half of the height of the machine, and a gold saving member 3 which is rotatably mounted on and supported by the fixed body member 2, and is also secured to an axial hollow shaft 4 that is rotatably mounted upon the base plate 1, and also a 20 fixed spider 5 that is arranged to support the upper end 4^A of the hollow shaft 4, of the gold saving rotating member 3. This hollow shaft 4 feeding the placer dirt to the rotating gold saving member as will 25 be presently described. These four members, the base plate 1 and the stationary body member 2 and the gold saving rotating member end and the spider 5 are all bolted together in operative relation by bolts 6, 30 which extend through apertures 6^A in the outside edge of the base plate 1 and through apertures 5^A in the outer ends of the spider arms and through tubes 6^B and through pipe fitting T members 3^A on opposite sides of 35 the gold saving member 3. This base plate 1 is rectangular in form being practically flat and thin relative to its size. Centrally of the width of the base plate, and near one 40 end thereof it is provided with a raised boss 1^A in which a recess 7 is formed, and a ball bearing bed plate 8 is inserted in the recess 7. The bed plate 8 is provided with a ball raceway in which a circumferential row of 45 steel balls 10 are seated and a top plate 11, which is preferably of a similar size is also provided with a ball race 12 in its under side which fits down over and against the balls in the ball race 9 of the plate 8 and together they form a ball bearing 13.

50 55 A flat flange which forms a part of a hub 13^A rests on top of the plate 11, and the hub extends loosely down through apertures 16 and 17 formed through the centers of the two ball-bearing plates 8 and 11, while the upper end of the hub 13^A projects above the plate 11 and is threaded and it screws into the lower end of the hollow steel 60 65 shaft 4.

The bolts 6, of which there are four, placed at equal distances apart around the

machine are preferably extended up from the bottom of the base plate 1. Consequently the heads of the bolts rest against the bottom side of the base plate and their threaded ends extend loosely up through 70 lugs 6^B formed on the ends of the spider arms 5, and nuts 6^C are screwed down against the surface of the lugs tight enough to clamp all of the main parts of the machine rigidly together. 75

The tubes 6^D that surround the bolts 6 are each made in two sections and the lower end of the lower section, of each of these tubes rests against the top surface of the bed plate 1, and their upper ends are 80 threaded and screw into the lower ends of the T's 3^A, through which the bolts 6 extend and are positioned at about a third of the length of the bolts 6 from their upper ends. 85

The second section of each of the tubes 6^D that surround the bolts 6 have their lower ends threaded and screw into the upper end of the T's 3^A, and their upper ends extend up to and bear against the under side of the 90 lugs 6^B of the spider arms 5.

The stationary body 2 is a hollow cylindrical housing, and its cap portion 15 is made independent of it, and is removably bolted to it by bolts 16^A, that extend through 95 their flanges 2^A and 17^A respectively. This cap 15 is made separate from the body 2, in order that gears 17^B and 18, which are mounted on shafts within this housing 2, can be placed in their relative operative positions as well as the ball bearing on the 100 top of the base plate and also that the lower end of the hollow shaft and its hub can be correctly positioned when the machine is assembled and at the same time to allow this 105 cap to be easily and quickly removed when repairs or new parts are needed within this housing 2.

A shaft 19, extends through a bearing 20, formed on one side of the housing 2, into the 110 housing far enough to receive a collar 21, and a pinion gear 18, which is secured to its inner end, and a gear 17^A, is rigidly mounted on the hollow rotating shaft 4 in a position to mesh with the pinion and be rotatably 115 driven by it.

The shaft 19 extends away from the bearing 20, of the housing 2, and is journaled in a bearing 22, that is formed on a standard 120 23, that is bolted on the outer end of the base plate 1, but which may, however, be cast integral with it if desired.

The shaft 19 can be connected to and rotatably driven by any kind of motor power mechanism but, I preferably illustrate a 125 tight and a loose pulley 24 and 25 mounted on said shaft in order that it may be driven by a belt from a pulley rotated by any rotative power.

The upper end of the hollow shaft 4 en- 130

ters a bearing aperture 26 in the axial center of the spider 5, and a depending packing box 5^a is formed on the spider concentric with the aperture 26. The packing box is externally threaded to receive a cap 5^b which bears against a gland 5^c which is inserted in the box. The upper end of the cap 15 of the housing 2 is flat and a ball bearing plate 27 is mounted loosely on the hollow shaft and rests on top of the upper end of the cap and it is provided with a ball raceway 28 and a circumferential row of balls 29 and a top plate 30, which is provided with a ball raceway 31, set on top of the circumferential row of balls 29. A large circular casting 32 sets on top of the upper plate 30 of this ball bearing and it is provided with an axial aperture 33 through which the shaft 4 passes. Upon the upper plate 30 of the ball bearing rests a divided octagonal collar 34 having a substantially square aperture the corners of which are rounded to fit the shaft 4 while the four straight edges of the aperture are adapted to fit into corresponding grooves or recesses 37 in the periphery of the shaft. The two halves of the collar 34 are held together in the recesses 37 by cap screws 36 which enter counterbored holes in the said halves, and are screwed into the shaft. This collar sets loosely into a corresponding recess 38, that is formed in the under side of the hub portion 39, of the bottom casting 32, and in assembling these parts the two halves of the divided collar are first placed in the recesses in the shaft and are secured there by the cap screws and then the bottom casting is placed down over the divided collar and when the bottom casting is down over the collar the collars cannot get out of the recess in the bottom casting as the hollow shaft is rotated by the power rotated gears it rotates the collar and the collar rotates the bottom casting, and in doing this the collar does not depend on the cap screws to hold it onto the hollow shaft as it fits snugly in the recess in the hub of the bottom casting and cannot get out of it.

The function of this collar is to positively rotate the casting 32, by the hollow shaft at the point where it rests on the ball bearing, and this is accomplished by means of the square collar being first secured to the shaft on its flat squared sides by the screws, and then being extended into the square recess in the bottom of the hub 39, of the bottom casting 32, then when the hollow shaft is rotated, it rotates the square collar and the square collar rotates the bottom casting.

A similar but octagonal shaped collar 40, is seated in an octagonal shaped recess formed in the hub 41, of the top cap casting 42, of the gold saving cylinder 3, and it is secured to flat places 43, formed on the hollow shaft by screws as in the case of the

collar 34 and the hollow shaft imparts its rotary movement to the cap 42, through the upper collar 40, and as this cap 42, is secured by the cap screws 44, to the top edge of the wall 45 of the cylinder 3, and as the bottom casting is secured to the cylinder by the cap screws 46, the hollow shaft rotates the cylinder 3, through the collars 34 and 40 as they rotate the bottom casting 32 and the cap 42 and they rotate the casing 45, which is secured between them, as the bottom 70 75 32 and the cap 42 and casing 45 form the complete cylinders.

The casting 32, that rests on and rotates on the ball bearing 30, forms the bottom 80 member of my gold saving cylinder and it is provided with a circular depression 78 which is semi-circular in cross section that forms a mercury holding pocket. This pocket is only a few inches deep in a machine of this size, but it communicates with a much larger chamber above it as will be presently explained. This bottom casting is provided with a projecting flange at its upper edge, which is bolted to a similar 85 flange, that projects from the bottom of a cylinder 45, which is in the form of a sleeve-shaped casting that is about fifteen inches in diameter and is about eleven and a half inches high, which at its upper end is bolted 90 to the cap casting of the cylinder by bolts 44.

The interior surface of this sleeve casting is provided with a series of special recesses and plain surfaces of preferably equal widths throughout most of its height, and they extend all around the interior of the sleeve.

A launder 49^a surrounds the upper portion of the casing 45, and comprises inner and outer concentric walls 48 and 49 respectively and a bottom member which inclines downwardly from the inner wall. This launder has four depending ears 108 which are bolted to the pipes 58 by bolts 109. The cap 42 is provided with a depending cylindrical wall 47 which extends into the launder 49^a to within a short distance of the said inclined bottom thereof. By this arrangement, the concentrates which discharge by centrifugal force from the upper end of the casing 45, together with any mercury and gold which may discharge with them are caught by the depending wall 47 and deflected into the launder 49^a, the mercury and gold settling to the lowest 115 point of the launder while the concentrates discharge through a spout 51, having a flange 54 provided with a projecting lug 53 which fits in a hole 52 in the outer wall of the launder, the spout registering with an 120 outlet opening in the said outer wall. A portion 55 of the spout flange extends into the outlet opening in the launder and engages the inner face of the outer wall of the launder, as shown.

The pipe fitting 3^A through which the bolts 6 pass are each provided with two threaded openings 56 and 57 which are arranged at right angles, and pipe sections 58 having threaded ends are screwed into opposite openings and thus form a square frame around the machine which braces the said bolts and prevents them from spreading.

10 A sleeve 59, surrounds the hollow shaft, and its lower end is seated in a counterbore 60, formed in the top of the hub portion 39 of the casting 32, through which the hollow shaft extends and this sleeve 59, extends up to the underside of the upper collar that is inserted in the cap 42, and is secured to the hollow shaft.

Between this sleeve 59, and the inside circumferential surface of the casing 61, there 20 is a circumferential space 62, that completely surrounds the sleeve 59, and this circular space forms a placer dirt receiving chamber except a narrow passageway 63, between the sleeve, and a flange 64, and the placer pulp 25 which is the placer sand and gravel and water enough to make a flowing stream is circulated by rapid rotation and centrifugal action throughout the cylinder and escapes from the cylinder through the passage 63, 30 and through a circular row of holes 64^A, that are formed in the bottom casting and through tubes 65, that are threaded at their upper ends into the holes 64^A and into a chamber 70 from which it discharges 35 through a spout 66.

The placer dirt tubes 65 convey the placer dirt past a horizontally positioned stationary plate 67, that is secured to the upper end of a circular ring 68, the plate being 40 provided with a projecting annular flange 69, that projects up around the lower end portions of the tubes. The ring 68 forms a chamber 70, the bottom of which is formed by the conical portion of the cap 15, and 45 from the chamber 70 the dirt discharges through the spout 66, the inner end of which is threaded into a hole 71, that is formed through the ring 68. An annular mercury catching space 72 is formed in the chamber 50 70 below the plane of the discharge and spout between the conical portion of the cap and the ring 68, which is adapted to catch any mercury that may escape out of the pockets in the bottom casting 32, and out 55 of the gold saving rotating cylinders.

The space between the sleeve 59 and the inner fluted surface 73, of the rotating gold saving cylinder 45 contains a double ring member, which is made of two castings 61 60 and 75 that are secured together by an overlapping joint 76, at the upper end of the ring 61, which surrounds the sleeve 59 that fits around the hollow shaft 4, and the inside and outside members 61 and 75 of this 65 double ring are positioned at about equal

distances from the sleeve 59, and the fluted surface 73 of the cylinder 45 with which they rotate.

The lower end of the member 61 is provided with a horizontal flange 77 that projects toward the member 75, and partly over the circular mercury holding pocket 78 in the casting 32. The flange 77 has a circular boss which is seated in a circular recess 79 formed in the casting 32, and its circumferential edge terminates in a lip which lies close to the inner surface of a vertical, adjustable amalgamating cylinder 80.

75 The inside surface 81, of the outer members 75 is provided throughout the greater 80 part of its height, with annular mercury holding grooves 82. An additional mercury holding element 83 surrounds the upper end of the member 61, and is in the form of a 85 circular pocket V-shaped in cross section, and mercury is supplied to it through tubular bolts 84 which are screwed through threaded holes in the cap 42, and through the bottom of a water box, to be later described, and into a hole in the horizontal portion 74 of the member 75, which holes communicate with the pocket 83. The holes through the bolts 84, are normally closed by screws 85, which are screwed into the heads of said bolts, as clearly shown in Fig. 1.

95 A slight space is left between the rim of the pocket 83 and the horizontal portion 74 of the member 75, and the pocket rests on the heads of cap screws 86 which are screwed into the member 61.

100 The lower end of the amalgamating cylinder 80, extends into an annular recess 87, that is formed in the bottom of the mercury pocket 78, of the bottom casting 32, and its top end extends to within a short distance 105 of the under side of the top cross portion 74, of the outer member 75, and it is adjusted vertically by long cap screws 89, that are threaded up through the bottom of the mercury pocket casting 32, and extend up 110 against and are secured to a short horizontal plate portion 90, by cap screws 91. The circumferential edge of this horizontal plate portion 90, of the vertical amalgamation plate 80, projects upward to about even with 115 the top edge of the bottom mercury holding casting 32, and close enough to it to leave only a narrow passageway between its outer end and the mercury pocket for the mercury to move up through into the mercury cells 120 that are formed by the recesses 73, in the inner periphery of the rotating cylinder 3, as will be presently described.

125 The cap bolts 89, that extend up through the bottom of the mercury pocket in the bottom casting of the rotating cylinder extend a short distance below it and thus have a vertical movement that will move the lower end of this amalgamating plate up out of the groove in the bottom of the mercury 130

pocket in which it rests. This arrangement allows me to divide the mercury pocket 78, into two divisions as shown, and the mercury in the inner compartment of it will 5 move upward under the action of the rotary movement of the cylinder past the end 78^A, of the upwardly turned end of the flange 77, and into the mercury cells of the cylinder 80, while the mercury in the outer compartment of the pocket will move up past the upturned edge 90^A, of the flange 90, alongside and in contact with the mercury cells of the inside surface of the cylinder 45.

When it is desired to have the mercury in 15 the whole area of the pocket the cap screws 89 are turned to raise the lower edge of the plate out of the slot in the bottom of the pocket, then the mercury occupies the full width of the bottom of the pocket.

20 The placer dirt A is screened through preferably about one quarter of an inch mesh screen and is fed through a chute D into a hopper E, where it mixes with water from a pipe C, the lower end of said hopper fitting in the upper end of the pipe 92, and the placer pulp flows through the hopper down into the hollow shaft 4, which fills full of gravel and sand up to radial pipes that form nozzles 93, of which there are 25 preferably four which are passed through the flange 67, and are threaded in the sleeve 59, and also in the shell of the hollow shaft 4, to its interior and they discharge the placer gravel and sand from elbows 94, into 30 the space 95, between the flange 61, and the amalgamation plate 80, the flow of the placer dirt from them being aided by the suction caused by the centrifugal force and the rotary motion of the cylinder which is rotated 35 at from about one hundred to about four hundred and fifty revolutions per minute, depending on the character of the placer pulp.

40 A portion of the water that flows into the cylinder with the placer dirt is utilized to assist in carrying the concentrates through 45 their outlet 96, by means of an adjustable ring 97, which is constructed as follows:

The concentrates which may be of iron 50 and other metals and occasionally a few globules of mercury flow through the space 89, between the upper end of the outside casing of the rotating cylinder 3, and the ring 97, that has flanges 99, and 100, projecting therefrom. The upper flange 99, lies 55 in a recess formed in the under side of the cap 42, and is adjustably secured therein by cap screws 101, that are threaded into the lower ends of larger cap screws 102, that 60 are screwed into the said cap, and by turning these large cap screws in the cap 42 vertical adjustment of the ring 97 is effected. The other flange 100, extends to the upper 65 end portion of the casing 45, which is contracted in diameter at this point to form an

annular lip 103 beyond which the remaining surface is outwardly flared. The flange 100 has a beveled edge which extends to within a slight distance of the lip 103, and adjustment of the ring 97 increases or diminishes 70 the space between the lip 103 and the flange 100, thereby regulating the flow of concentrates between them. The concentrates after passing through the opening between these points, flow through the tapering slot 96, 75 between the cap 42 and the top of the casing 45 from which they run down into the launder 49^A, flowing against the inside of the depending flange 47, of the cap 42, and between it and the inner side 48, of the 80 launder, to its bottom and out of it through the concentrates discharge spout 51, while the mercury, should there be any, is trapped in the recess 55, just below the lower edge of the discharge spout.

85 The water box 104, is a ring shaped trough and is arranged to be raised and lowered in a ring shaped recess that is formed between a vertical inner side surface of the ring 97, and a vertical surface 105, formed on the 90 axial hub portion of the cap 42, and it is raised and lowered in its supporting ring shaped recess by cap screws 84^A, that are threaded down through the cap 42, and extend to the inside surface of the water box 95 104, and are secured to its bottom by cap screws 84^B, see Figure 14, that extend loosely up through the bottom of the water box and are threaded into it.

This water box is provided with a circular row of water inlet apertures 106, which are placed in its inner circumferential flange and they are positioned to admit water to it close to its bottom, and this water flows out of this water box through a circumferential row of somewhat smaller apertures 107 that are formed through the body portion of the ring 97, from which the water and the concentrates flow through the tapering slot 96, which is a circumferential slot 110 except that there are raised lugs L, on it that fit up against the under side of the cap 42, and this tapering slot in the top of the casing 45 on the cylinder 3, can be made as much wider than the proportion shown as 115 desired by adding thin washers between its lug portions L, and the under side of the cap, on the cap screws 44.

The concentrates flow from the passage at 98 through the space 96, at the top or the upper edge of the rotating cylinder and then drop down into the launder 49^A, and flow out of the spout 51, and the launder is provided below the bottom of its mercury catching pocket with four depending ears 125 108, that are bolted to the horizontal pipes 58, by bolts 109, that extend through the flange and the pipes. While it is not expected that there will be mercury globules in the concentrates yet a few may be carried 130

over during continuous running between the time of shutting down and cleaning up the amalgamating plates, and they will run into and be caught in the pocket 55, in the bottom 5 of the launder below the lower edge of the discharge spout.

The operation of my mineral hydro extractor is as follows:

First: The circular trough or pocket 78, of the bottom casting are filled with mercury; then the desired rotative movement is given to the amalgamating cylinder, and then the placer gravel and sand which have been given a screening treatment by a mechanism which I do not illustrate, but which may consist of either a grizzly or a wire screening apparatus or both, in which they are reduced to a product of about from one eighth to a quarter of an inch mesh, depending on the character of the placer deposit, and they are then conveyed into a hopper E, together with a supply of water that is sufficient in volume, when mixed with the sand and gravel of this mesh, to form an easily and quickly flowing placer pulp stream, which discharges from the bottom of the hopper, which fits into the end of a short pipe 92, which is screwed into an aperture 110, that is formed in the axial center of the top of the spider 5, and the material then flows down through this aperture and into the hollow shaft which it fills up full permanently with the sand and gravel level with the pipes 93, through which it runs into the amalgamating cylinder 80. The now thoroughly mixed material flow upward in this cylinder 80 in the direction of the arrow F, and in contact with its mercury holding grooves 81, and over the top of it, and down into the space 40 112 between it and the member 75, in the direction of the arrow G, and in contact with the mercury holding grooves 113, in this member 75, and then around the lower end of the member 75, and upward between the outside, of this flange and the inside surface S, of the outside casing 45, of the rotating cylinder 3, in the direction of the arrow H, and in contact with its numerous mercury holding grooves 73, and the concentrates flow through the space 98, between the upper end of the casing 45, and the vertically adjusting ring 97, and then through the space 96, at the top of the casing 45, of the rotating cylinder 3, and the under side 50 of the cap 42, and then into the launder and out of the spout 51, while the mixed tailings water and sand and gravel flow around the top of a short vertical flange 114, that projects from the flange 88, and follows the passage 115, between the top of this flange 114, and the bottom of the water box 104, and then around the corner of the flange 74, down into the outlet passageway 62, in the direction of the arrow I, and between the 60 outside surface of, the flange 61, and the ad-

jacent sleeve 59, that surrounds closely the hollow shaft 4, and through the apertures in the bottom casting and into and through the tubes 65, of which there are ten, which connect with the ten cored holes 64^A, in the bottom casting of the rotating amalgamating and concentrates forming cylinder 3, and from the ten tubes 65, the edge 116, of each of which forms an orifice point that turns the tailings in the direction of the arrow 75 up against the underside of the flange 67, and allows all of the tailings to flow in an even stream into the chamber around the cap 15, of the stationary frame 2, and from it out to waste or further treatment through the spout 66.

As the easily flowing tailings water and sand and gravel flow past the inner corner of, the water box, water surges up through and into the corner space 117, and a portion 85 of it flows and in fact is drawn into the water box through the numerous inlet holes 106, by the suction of the centrifugal force on the rapidly rotating cylinder 3, and keeps it full and also carries it with enough 90 force to flow out of the water box through the circular row of small holes 107, in the vertically adjustable ring 97 and it discharges from it into the space 118, above and helps force the concentrates that flow into 95 this slot through the slot 96, over the top or the outside casing of the rotating cylinder into the launder 49^A, and out of it through the spout 51, as above described.

The mercury holding recess 78, in the bottom casting is filled with mercury through the apertures 119, of which there are preferably two, which are placed on the opposite sides of the bottom casting, as I have found that the mercury can be better balanced if 100 it is entered in equal amounts from opposite sides of the pockets. When the cylinder is 105 rotating at the speed best adapted to separate the gold and silver metals from the placer sand and gravel, the mercury travels by 110 means of centrifugal action up the mercury holding cell provided inside surface S, of the outside casing of the cylinder into its cell 73, which it fills, and down the inside surface of the cylindrical member 75, and fills its cells 115 full of mercury, and also up the inside surface of the amalgamating cylinder 80, and fills its cells full of mercury. The mercury holding ring shaped pocket surrounding the upper end of the member 61, which is 120 filled with mercury through the tube 84, discharges its mercury through a narrow space 125 120, between its top edge, and the under side of the flange 74, under the centrifugal force developed by the rapidly rotating cylinder, and this mercury will flow down and work 130 into the cells of the cylinder 75. As the mixed water sand and gravel flows continuously through the circuitous passageways indicated by the arrows and as above described, 130

- the gold in it works outwardly through it to the mercury filled cells 81, 113 and 73, and becomes amalgamated with it, and the amalgam falls down from them into the mercury 5 pockets 78, from its weight, and at the same time the mercury is working continuously up into the cells, while the platinum and silver carbonates, the grains of lead, zinc, iron and particles of other metals are concentrated 10 into concentrates and flow in their watery carrying fluid out through the space 98, between the points 100, and 103, and across the space 118, at the top of the outside casing into the launder 49^A, and out of the spout. 15 The gold amalgam is drawn out of the mercury pockets 78, from time to time through the apertures 121, of which there are three that are normally closed by cap screws 122, see Figure 13. The lower end of the amalgamating cylinder 80, should be raised 20 enough to allow the mercury to flow evenly underneath its lower end to allow the mercury to stand at a level on both sides of the lower end of the plate, which can then be 25 lowered back into its recess, if it is desired to divide the pocket into two compartments.

And while the mercury is poured into this pocket through the apertures 119, which are normally closed by cap screws 120, it can be 30 seen that unless the lower end of this partition is raised the mercury cannot flow from the outside of these pockets to the inside of them. Consequently, if it is to be divided, the mercury must first be allowed to flow to 35 fill the entire width of the mercury holding pocket and then afterwards the plate can be lowered to divide the pocket into two compartments, each of which will contain a supply of mercury.

Gold, platinum and other metals will settle in the course of time into the sand and gravel that fills the hollow shaft from its hub 15, up to the three water and placer sand and gravel inlet pipes 93, and once in 45 a while this hollow shaft can be taken out and the hub removed and the sand and gravel with its gold and platinum and metals can be removed from it and its gold and platinum can be recovered from it by hand panning, or it can be placed in the hopper with 50 the inflowing placer gravel and run through the rotating cylinder.

My centrifugal amalgamating and concentrating machine will save the finest gold that exists in placer deposits, and it is so constructed that the amalgam can be extracted from it without taking it apart, and the concentrates it makes will flow automatically from it, and its tailings can be conveyed 55 from it to a cyanide, or a flotation, or to a chemical, or to a roasting treatment followed by any of the above treatments, and in addition it can be used to amalgamate the gold, and to save and collect the fine grains 60 of rusty gold or gold covered with a chemi-

cal deposit that will not amalgamate with mercury by concentrating it, and it will also collect the fine grains of platinum and other metals into concentrates from ores mined from fissure and other veins, which can be 70 crushed to the mesh best suited to run through my mineral hydro-extractor, and also all refractory ores carrying gold if first crushed fine and then roasted will yield as 75 a rule over ninety per cent. of their gold values if run through my mineral hydro-extractor, and tailings of stamp and flotation and other ore treating mills can be run through it.

My invention provides a compact machine that can be shipped in small easily portable packages or boxes, and can be easily and quickly set up, and can be operated by steam, or electric or water or gasoline engine power; and while I have illustrated and described the preferred construction and arrangement of the mineral hydro-extractor, I do not wish to be limited to the construction and arrangement shown as many changes may be made in it without departing from 90 the spirit of my invention.

Having described my invention, what I claim as new and desire to secure by Letters Patent is:

1. A centrifugal concentrator and amalgamator, comprising a rotatable cylinder having a plurality of annular mercury holding grooves in its inner face, a circular mercury pocket at the bottom of said cylinder, spaced cylindrical amalgamating units 95 in said cylinder provided with mercury holding grooves, means for dividing the mercury pocket into two annular pockets, means for delivering pulp to the innermost amalgamating unit, means for separating the inflowing pulp from the mercury in the mercury holding pocket in its passage through said units and through said cylinder, means for permitting the discharge of the concentrates from the upper end of the 100 outer cylinder, means for rotating said cylinders and means for discharging the tailings from the bottom of said cylinder, said mercury pocket having normally closed outlets. 105

2. A centrifugal amalgamator and concentrator comprising an outer rotatable cylinder having a plurality of annular mercury holding grooves in its inner face, a mercury holding pocket at the bottom of 110 said cylinder, a vertical cylinder member extending into said mercury pocket to divide the same into two compartments, said member having a plurality of annular mercury holding grooves in its inner face, means for raising said member to change the two compartments into a single compartment, said cylindrical member having a horizontal plate which extends over the top of said mercury pocket and close to the inner face 115 120 125 130

of said cylinder, a double cylinder element secured to the bottom of said outer cylinder, whose outer member extends up into the outer cylinder and is spaced from the same and having its outer member extend over and down within said adjustable member and spaced from the same, said outer member being provided in its inner face with a plurality of mercury holding grooves, its lower end terminating a short distance from said horizontal plate, a cap removably secured to the top of said cylinder, a passage way being provided between the cap and the top of said double cylinder element and between the cap and the rim of the outer cylinder, and means for feeding material to the interior of said vertical cylinder member.

3. In a centrifugal amalgamator and concentrator the combination with a hollow shaft, spaced concentric concentrating and amalgamating cylinders connected to said shaft feed pipes connecting the shaft and the interior of the innermost cylinder and a cap on the outer cylinder, an outlet passage being defined between said cap and cylinder; of an adjustable ring on the outer cylinder for defining an annular concentrates outlet to said outlet passage, an annular water box within said ring having water inlets said ring having apertures connecting the water box and the said outlet passage, a tailings outlet from said cylinders, means for supplying material to said hollow shaft and means for rotating said shaft.

4. The combination with a shaft, means for rotating the same, spaced amalgamating and concentrating cylinders surrounding said shaft and movable therewith, means for discharging pulp into the innermost cylinder, means for discharging concentrates from the top of the outer cylinder, means for discharging tailings through the inner portion of the bottom of said cylinder, said bottom having a mercury supply pocket therein, and means for permitting the removal of amalgam from said bottom.

5. In apparatus of the character described, the combination with a hollow rotatable vertical shaft; of a series of spaced concentric vertically disposed concentrating and amalgamating cylinders mounted on said shaft, an adjustable ring in the top of the outer cylinder which defines a concentrates outlet, a sleeve in the inner cylinder which surrounds said shaft and is spaced therefrom to form a tailings outlet a connecting passage being formed between said outlet and the upper portion of the outer cylinder, radial discharge pipes extending from the hollow shaft through said sleeve to the interior of the inner cylinder, and means for supplying material to the hollow shaft, said material being carried from cylinder to cylinder under centrifugal action.

6. In apparatus of the character described the combination with a hollow rotatable vertical shaft of a concentrating and amalgamating cylinder having a bottom cap axially mounted on said shaft, a sleeve supported on said cap and surrounding said shaft but spaced therefrom, a mercury pocket surrounding the upper portion of said sleeve a second amalgamating and concentrating cylinder within the first cylinder and spaced therefrom, and having a horizontal portion adjacent its upper end, which connects with said sleeve; a third cylinder within the second cylinder and spaced therefrom and supported on the bottom cap, radial pipes extending from the hollow shaft through said sleeve and into the innermost cylinder, an adjustable ring-like member in the top of the outer cylinder, which defines a circular concentrates outlet, an annular mercury pocket in said bottom cap, the space surrounding the shaft being connected by a passage at its upper end with the upper end of the outer cylinder, and at its lower end with outlets in said cap, and means for supplying material to said hollow shaft.

7. In apparatus of the character described, the combination with a hollow rotatable vertical shaft, a series of spaced concentric concentrating and amalgamating cylinders mounted thereon and pipes connecting said hollow shaft and the interior of the innermost cylinder, said hollow shaft being adapted to receive a continuous supply of pulp; of an adjustable cap on the upper end of the outer cylinder having a depending portion which surrounds the cylinder but is spaced therefrom, an adjustable ring in said cap which acts in conjunction with the rim of said cylinder to define an annular concentrates outlet, means defining a tailings outlet passage surrounding the hollow shaft and connected at its upper end with the upper portion of the outlet cylinder, and a bottom cap for the outer cylinder having outlets connected with said tailings outlet passage.

8. In apparatus of the character described, the combination with a hollow rotatable vertical shaft, a bottom cap axially mounted on said shaft and secured thereto, an outer cylinder secured to said cap, a top cap axially mounted upon and secured to the hollow shaft and adjustably connected to the rim of said cylinder, a second cylinder spaced from the outer cylinder having a horizontal portion near its upper end and a tube surrounding but spaced from the shaft and connected at its upper end to the said horizontal portion and at its lower end to the bottom cap, openings being provided which extend from said space through said cap; a third cylinder adjustably supported in the bottom cap and terminating near the

top of the second cylinder and spaced from said cylinder, a flange on the innermost cylinder which extends below the second cylinder, to within a slight distance of the outer cylinder a flange on the lower end of the tube which extends to within a slight distance of the innermost cylinder, said flanges having annular lips, pipes connecting the interior of the hollow shaft with the 10 interior of the innermost cylinder, adjustable means defining a concentrates outlet at the top of the outer cylinder, said lower cap constituting a mercury pocket and said cylinders being provided with annular 15 mercury-receiving grooves, and said shaft being adapted to receive a continuous supply of pulp.

9. In apparatus of the character described, the combination with a hollow rotatable shaft and a series of spaced concentric amalgamating and concentrating cylinders, of a cap adjustably connected to the rim of the outer cylinder and having a hub secured on said shaft, an adjustable ring 25 in said cap which acts in conjunction with the rim of the outer cylinder to define an annular outlet, a vertically adjustable water box interposed between the inner face of said ring and said hub, apertures being 30 formed in the inner wall of said box and said ring, a cap secured to the lower end of the outer cylinder having a hub secured on said shaft, said cap constituting a mercury pocket, pipes connecting the 35 interior of the shaft and the interior of the innermost cylinder, means defining an outlet surrounding the shaft and connecting with the upper portion of the outer cylinder and with outlets in the bottom cap, said shaft being adapted to receive a continuous 40 supply of pulp.

10. In apparatus of the character described, the combination with an amalgamating and concentrating cylinder having 45 hubbed caps and a rotatable shaft which passes axially through said hubs, of means for locking said caps to said shaft, comprising divided octagonal collars and which are secured together to said shaft, said collars

fitting into corresponding recesses in the 50 hubs of said caps.

11. In apparatus of the character described, a hollow rotatable shaft, a cylinder axially mounted on said shaft having upper and lower caps; the upper cap being 55 adjustably spaced from the rim of the cylinder, the lower cap having a circular mercury pocket which is semicircular in cross section, a tubular member which surrounds the shaft but is spaced from the 60 same to form an outlet passage connecting with outlets in said bottom cap, said tubular portion having a horizontal flange at its upper end from which depends a cylinder, a cylinder within and spaced from the latter 65 cylinder, its lower end resting in an annular groove in said mercury pocket, means for raising said cylinder out of said groove, adjustable means defining an annular outlet at the top of the outer cylinder, means defining 70 a passage in the upper end of the outer cylinder which connects with the passage surrounding the shaft, pipes connecting the shaft and the innermost cylinder, said cylinders having annular mercury receiving grooves.

12. In apparatus of the character described, a hollow shaft, a cylinder axially mounted on said shaft, a second cylinder, spaced from the first cylinder and having a 80 horizontal flange at its upper end which is provided with a tubular portion surrounding said shaft but spaced from the same to form an outlet passage which connects with outlets in the bottom of the first cylinder, 85 a mercury pocket surrounding the said tubular portion adjacent the horizontal flange, hollow bolts which extend through the top of the outer cylinder and into holes in the horizontal flange, whereby mercury is supplied to said pocket, adjustable means defining an annular outlet at the top of the outer cylinder, and pipes connecting the hollow shaft and the inner cylinder, said cylinders having mercury-receiving grooves. 90 95

In testimony whereof I affix my signature.

FRANK D. LEWIS.
